UNITED STATES PATENT OFFICE.

HENRI JEAN JOSEPH MARIE DE REGNAULD DE BELLESCIZE, OF TOULON, FRANCE.

CIRCUIT RECEIVER.

(GRANTED UNDER THE PROVISIONS OF THE ACT OF MARCH 3, 1921, 41 STAT. L., 1313.)

Application filed August 14, 1918. Serial No. 249,910.

To all whom it may concern:

Be it known that I, HENRI JEAN JOSEPH MARIE DE REGNAULD DE BELLESCIZE, a citizen of the French Republic, residing at No. 5 24, Rue Victor Clappier, at Toulon, Var, France, have invented certain new and useful Improvements in Circuit Receivers (for which I have filed applications in France, Patent No. 495,316, June 26, 1917; in Germany, R. 47,955, July 11, 1919; in Great Britain, Patent No. 132,434, Feb. 11, 1919; in Argentina, 16465, Aug. 14, 1919; in Belgium, H. 1884/403, July 1, 1919; in Belgian Congo, 534, July 2, 1919; in Italy, 15 261/1144, June 25, 1918; in Norway, 35,003, July 29, 1919; and in Brazil, 10,747, Sept. 23, 1919), of which the following is a specification.

An ordinary receiver mounting, such as 20 shown on Fig. 1, comprises a closed circuit LC conductively connected by means of a self induction a with the self induction L' of a second closed circuit $L'C'$, to the terminals of which the detector P and indicator 25 Q are connected; the primary LC itself may be with a closed antennæ, for example a frame, or an intermediate circuit actuated by other circuits not shown.

Figs. 2 and 3 represent the same mounting modified in accordance with the present 30 invention.

The ordinary mounting of Fig. 1 presents defects which may be analyzed as follows: In addition to the normal induction between 35 the self induction a and L' due to the principal current I , which circulates around the closed circuit LC, said latter creates on the secondary $L'C'$ two other parasitic actions. The first parasitic action is electrostatic; the 40 self induction a has, in fact, with respect to the self induction L' , a slight intrinsic capacity C''' shown in dotted lines; in order that this connection C''' have no effect it is necessary that the potential of the self 45 induction a be stabilized, which can not take place in an ordinary mounting. The second parasitic action existing between the circuits LC, $L'C'$ is inductive; in fact, by 50 reason of the dissymmetrical position of the self induction a with respect to the main condenser C, and of the capacity, with respect to the ground as well as with respect to the adjacent circuits, distributed along 55 the primary, the self induction a is traversed, besides the normal current I , by a

parasitic current i shown in dotted lines, and the inductive action of which on L' can not be disregarded; this current i has an unknown period, differing in all cases 60 from the normal period

$$T = 2\pi\sqrt{LC} = 2\pi\sqrt{L'C'}$$

common to the two closed circuits. In addition to these two parasitic actions which 65 it receives from the primary circuit, the secondary $L'C'$ itself creates a third, due to the dissymmetry of the detector and indicator devices; this is seen clearly on the drawing on Fig. 1, which shows, by way of 70 example, a three electrode valve P actuating a telephone Q; while the network and the short wire connecting it to the armature n of the condenser C' offer an altogether negligible capacity, the other armature m is connected to an assemblage (filament, plate, sources $S_1 S_2$, telephone Q, operator not shown) which is very bulky and which offers with respect to the ground a generally complicated connection, diagrammatically represented by the imaginary condenser C'''; this connection prevents the 75 oscillations of potential at m and n from having the same amplitude, which is denoted, between these two points, by a new 80 parasitic current affecting the detector; it amounts to the same as saying that to the closed oscillators LC and $L'C'$ there is superposed a new open oscillator, formed, in the present example, by the assemblage 85 LC, the connection C''', the assemblage $L'C'$, the connection C'' and the earth; this open oscillator, generally greatly damped, also has a new unknown period, differing 90 from

$$2\pi\sqrt{LC} = 2\pi\sqrt{L'C'}$$

peculiar to the closed circuits.

The dissymmetries above referred to have a first drawback which is common to these 100 kinds of arrangements, viz., the impossibility of realizing tuning only with one pre-determined transmission, since the receiving circuits have several natural frequencies. Moreover, such circuits are susceptible of being rendered oscillatory directly through the ground, which renders ineffective the devices in which the energy has to pass successively through various circuits, such as LC and $L'C'$, in which the sharpness 105 of tuning has to be gradually in-

creased; it is therefore impossible to eliminate in such a receiver very powerful waves of a different length from that of the waves which are to be received.

- 5 A second drawback refers to the closed circuits of radiogoniometric receivers. As pointed out above, the effect of the dissymmetry of the circuit is to superpose upon the main oscillation of the circuit, the oscillation corresponding to an open aerial having a certain height relatively to the ground. The result thereof is that when trying to find the direction of the waves which are received, the reception cannot be completely 10 eliminated, and it passes through a minimum for a direction which is not exact. In fact, if the aerial receiver is assumed as formed by a closed receiving frame LC, the sound produced by a signal is nullified 15 when the plane of the frame is orientated in such manner as to contain the lines of force of the magnetic field produced by this emission. In fact, if G indicates the angle which the plane of the frame makes 20 with the field the electromotive force F induced in the receiver may be represented by the known expression $F = A \sin G \sin (\omega t + y)$ where A is a coefficient proportional to the surface of the frame, ω is 2π 25 the frequency, y the phase of the current in the closed frame. This expression is nullified for $G=0$; an indicator on the frame and perpendicular to its plane then points exactly in the direction of the emitter post. 30 But if an open aerial (antenna) becomes superposed to the closed frame, the total E. M. F. developed in the circuit has the formula 35
- $$F = A \sin G \sin (\omega t + \varphi) + B \sin (\omega t + \psi)$$
- 40 where B is coefficient proportional to the effective height of the open antenna (aerial), ψ the phase of the current in this antenna. This expression does not become zero and 45 passes through a minimum for a value of G which is unknown and different from zero; consequently when the sound produced by the signal is minimum, the indicator makes an angle with the direction of the 50 station to be connected unknown to the operator.

A third drawback refers also to closed aerial circuits; such circuits are connected to earth in a dissymmetric manner which 55 produces, besides the normal aerial, a new open one non-directional and very damped; consequently, the circuits become more susceptible to being influenced by the disturbances of atmospheric or telluric origins 60 which generally are also very damped and deprived of a natural frequency.

The present invention has for its object to remove the drawbacks referred to and it is hence proposed to render symmetrical the 65 connections between the condenser C' and

the ground; and to nullify the two parasitic actions which, in accordance with the above statement, are exerted between the primary LC and the secondary $L'C'$.

Figs. 2 and 3 clearly illustrate the new 70 procedures set forth.

The symmetry of the connection between the condenser C' and the ground is obtained as follows: Upon the connecting wire n is placed a combination D of capacities, resistances and self inductances which reproduces the characteristics of the apparatus and operator connected with the wire m . The compensation is effected either with respect to the ground or with respect to Faraday's cage, if the receiving circuit is enclosed in such a cage. The combination D varies according to the mounting; it is generally complicated; this is mainly due to the fact that certain apparatus, for instance the telephone, which effects a coupling between the operator and the ground have a capacity distributed along the windings, the impedance of which also varies with the frequency of the oscillation. Therefore, it 80 is always to be recommended to reduce to a negligible value the corresponding dissymmetry which is to be eliminated. For instance, the effect of the operator may be (Fig. 3) attenuated by shunting the head 85 gear on a transformer K with separate circuits, forming a small capacity with each other; by using choking coils JJ stopping the passage of high frequency currents, by causing the rectified current to act upon a 90 microphone relay, etc. In a manner, the connection between the wire m and the ground becomes a pure capacity c'' due to the volume of the sources $S_1 S_2$; it is balanced by placing on the other wire n a condenser D of capacity equal to C'' ; this is 95 shown in Fig. 3.

To nullify two parasitic actions between the primary LC and the secondary $L'C'$, use is made of two arrangements, both essential, and shown in Figs. 2 and 3.

The first arrangement consists in coupling the circuits by means of two identical coils a and b fulfilling the following conditions; they shall be placed in the circuit LC in 115 such a manner that they shall be electrically symmetrical relatively to the capacity C ; they shall influence with the same coupling the same part of the secondary coil L' in such a manner that the induction effects between aL' and bL' shall assist each other, for the normal current I . By reason of the symmetry the two weak parasitic currents i_x and i_y flowing to the ground or the Faraday cage Z are, one in the same direction, the other in the opposite direction to the normal current I ; the inductive actions of these parasitic currents on the secondary self induction L' are opposed to 120 each other and nullify each other. 125

The second essential arrangement to nullify the parasitic actions between the circuits, consists in stabilizing the potential of the primary circuit; which is obtained by 5 connecting one of its points suitably chosen to earth or with the Faraday's cage Z, which protects the receiving system. The consequence thereof is that the electrostatic coupling effected between the self-inductances 10 a, b and the secondary L' is diminished or eliminated. Two different arrangements carrying this improvement into effect are indicated by way of example in Figs. 2 and 15 3 of the accompanying drawings. In the arrangement illustrated in Fig. 2, the middle M of the self inductance L of the primary circuit is connected to earth, the potential of this point is constant; but this is not generally strictly so, so far as the self-inductances a, b are concerned, since between 20 them and the point M there are conductors in which appreciable electromotive forces may be induced; these conductors have, in fact, a high self induction equal to $\frac{L}{2}$; although 25 greatly reduced, the effect of the electrostatic coupling between the primary and the secondary circuits is not yet strictly nil. In the arrangement illustrated in Fig. 30 3, the potential of a point N immediately close to the secondary circuit is stabilized; the disturbing effect is then reduced to a minimum; the primary condenser C is arranged in the middle of the self-inductance 35 L; it will be obvious that this arrangement requires certain special features of construction in order to attain its maximum efficiency; in the case where similar precautions are justified, all the apparatus other 40 than the frame L must be enclosed in a Faraday's cage Z; no conductor which is carrying an oscillatory potential drop must penetrate into this cage and more especially the primary condenser C must be placed out- 45 side and kept at a distance; in Fig. 3, in which these prescriptions are observed, the only parts of the aerial penetrating in the Faraday cage are the connecting coils a, b; now the potential of the point N comprised 50 between these coils is nullified by connection with the ground; the coils themselves, intended exclusively for connecting with respect to the secondary, have a self induction extremely slight with respect to the 55 total self induction L of the primary, so that the tension developed there is only a negligible fraction ($\frac{1}{500}$ in average application) of the total oscillating potential drop set in 60 operation in the primary circuit. Consequently, no appreciable electrostatic effect will develop between the primary and secondary.

It will be obvious that these arrangements 65 differ entirely both with respect to the mode

of carrying them into effect and with respect to the object in view, from those which are usually employed and which consist in earthing a certain point of a frame; in fact, this latter arrangement had till now the effect of increasing the dissymmetry of the primary aerial circuit; its object was for example, to facilitate the finding of the signals coming from unknown directions by suppressing the disappearance of the sound, 70 which is produced for certain azimuths. In contradistinction thereto, the arrangements described in the present patent have the object of realizing a perfect symmetry in order to obtain, for example, the total extinction of a disturbing transmission. 75 80

I claim—

1. In the construction of radiotelegraphic receivers comprising a self inductor and a capacity forming an oscillating circuit in 85 connection with an indicator circuit, a method consisting of balancing the external electrostatic actions on all of the elements of the receiving apparatus, so that these actions may be distributed symmetrically with 90 respect to said capacity.

2. A receiver for wireless telegraph comprising a condenser, a closed circuit including a coil mounted in series with the condenser, and an indicating device connected 95 to the terminals of said condenser; the conductors connected to one of the terminals of the condenser comprising a combination of self induction coils, condensers and resistances the electrical characteristics of which 100 reproduce the electrical characteristics of the apparatus connected on the other terminal of the condenser, so as to render the circuit exactly symmetrical electrically with respect to the condenser. 105

3. A receiver for wireless telegraphy comprising, in combination, a main condenser, a closed circuit including a coil mounted in series with this condenser, and an indicating device connected to the terminals of said 110 condenser; a second small condenser being inserted between one of the terminals of the main condenser and the earth, and the capacity of the apparatus being connected to the other terminal of the main condenser 115 so as to render the circuit exactly symmetrical electrically with respect to the main condenser.

4. A closed circuit receiver comprising, in combination with a main self induction coil 120 and a condenser in series therewith, a self induction acting as a secondary with respect to the closed circuit; the two coupling coils being positioned symmetrically with respect to the condenser, the conductors connecting 125 said coils to the condenser having the same electrical characteristics; said coupling coils being in addition identical with each other and operating with identical inductive connections on the same part of the secondary 130

self induction, and the inductive effects of the coupling coils being additional.

5. A closed circuit receiver comprising, in combination with a main self induction coil and a condenser in series therewith, two connecting coils connecting the circuit inductively with a self induction playing the part of a secondary with respect to the closed circuit; the two connecting coils being positioned symmetrically with respect to the condenser, the conductors connecting the coils to the condenser having the same electrical characteristics; said connecting coils being, in addition, identical with each other and operating with identical inductive connections on the same part of the secondary self induction coil and their inductive effects being additional, and said closed circuit receiver being electrically connected to the ground in a completely symmetrical manner with respect to the condenser as well as with the connection coils.

6. A closed circuit receiver comprising, in combination with a main self induction coil and a condenser in series therewith, two connecting coils connecting the circuit inductively with a self induction playing the part of a secondary with respect to the closed circuit; said coupling coils being positioned symmetrically with respect to the condenser, the conductors connecting the coils to the condenser having the the same electrical characteristics; said connecting coils, in addition, being identical with each other and operating with identical inductive connec-

tions on the same part of the secondary self induction, the inductive effects of the coils being additional, and a ground wire leading from the circuit and arranged symmetrically with respect to the condenser and the connecting coils.

7. A closed circuit receiver, comprising, in combination with a principal self induction and a condenser in series with said self induction, two connecting coils conductively connecting the primary circuit with a secondary circuit comprising a self induction, a condenser in series with the self induction, and an indicator device connected to the terminals of this condenser, the secondary circuit moreover being exactly symmetrical, from an electrical view point, with respect to its condenser, the two connecting coils being positioned symmetrically with respect to the primary condenser, the conductors connecting the coils to this condenser having the same electrical characteristics; said connecting coils being in addition, identical with each other and operating with identical inductive connections on the same part of the secondary self induction, and their inductive effects being additional; and said primary circuit receiver being electrically connected to the ground in a completely symmetrical manner with respect to its condenser as well as with the connecting coils.

In testimony whereof I have signed my name to this specification.

HENRI JEAN JOSEPH MARIE
de REGNAULD de BELLESCIZE.
